Patented June 30, 1964

198,529

ELECTRICAL PLUG FOR TELEVISION LEAD-IN WIRE

Raymond L. Lewis, 9233 Highland Ave.,
Bellflower, Calif.

Filed Jan. 13, 1964, Ser. No. 78,195

Term of patent 14 years

(Cl. D26—1)

Fig. 1.

Fig. 2.

Fig. 3.

Fig. 4.

Fig. 5.

FIG. 1 is a perspective view of one end of the electrical plug for television lead-in wire showing my new design;

FIG. 2 is a top plan view of one side thereof;

FIG. 3 is a side elevation thereof;

FIG. 4 is an elevation of one end thereof; and

FIG. 5 is an elevation of the opposite end thereof.

I claim:

The ornamental design for an electrical plug for television lead-in wire, substantially as shown.
